(57) **CLAIM**

The ornamental design for a steel door panel grouping, as shown and described.

DESCRIPTION

FIG. 1 is a front view of a steel door panel grouping, the broken lines are for purposes of showing the environment of a door and form no part of the claimed design; FIG. 2 is a perspective view thereof; and, FIG. 3 is a cross-sectional view taken along line 3—3 of FIG. 1, which applies to each panel shown in FIG. 1.
